UNITED STATES PATENT OFFICE.

LOUIS H. HAYS, OF CLEVELAND, OHIO, ASSIGNOR TO THE KAYNEE COMPANY, OF CLEVELAND, OHIO, A CORPORATION OF OHIO.

COMBINATION-GARMENT.

1,221,051.

Specification of Letters Patent. Patented Apr. 3, 1917.

Application filed July 6, 1915. Serial No. 38,043.

To all whom it may concern:

Be it known that I, LOUIS H. HAYS, a citizen of the United States, and a resident of Cleveland, county of Cuyahoga, and State 5 of Ohio, have invented a new and useful Improvement in Combination-Garments, of which the following is a specification, the principle of the invention being herein explained and the best mode in which I have 10 contemplated applying that principle, so as to distinguish it from other inventions.

The present improved garment is a form of under garment more specially for children's wear, and is designed to combine the 15 functions of two or more garments ordinarily worn in this connection. One particular object of the invention is to provide in a single garment means for supporting certain of the outer garments, including 20 more specially stockings and trousers, all from this one undergarment, the latter being arranged so that the weight of the attached garments is supported from the shoulders of the wearer without any con- 25 striction of the waist or dragging effect on the sides. To the accomplishment of the foregoing and related ends the invention, then, consists of the means hereinafter more fully described and particularly pointed out 30 in claims.

The annexed drawing and the following description set forth in detail certain means embodying the invention, such disclosed structure constituting, however, but one of 35 various mechanical forms in which the principle of the invention may be used.

In said annexed drawing:

Figure 1 is a front elevational view of my present improved garment; and Fig. 2 is a 40 rear elevation of the same.

Referring to the aforesaid figures of the aforesaid drawing, the garment will be seen to comprise in effect a pair of drawers 1 and, integral therewith, a waist 2, the latter being 45 of the approved armless form, its upper portion consisting simply of straps 3 adapted to pass over the shoulders. These straps are transversely severed, the ends being secured together by means of buttons 4 and 50 button holes 5, of which latter a plurality is provided in each strap, suitably spaced to permit of adjustment, as will be readily understood.

Sewed into the material of the waist are 55 two bands 6, or relatively wide strips of

tape, which pass over the shoulders, respectively, the buttons 4 being attached through such band and the button holes 5 also being formed therein. The lower ends of these bands are sewed into, and thus firmly attached to another encircling band 7, which constitutes a waist-band so that the first-named bands that thus pass over the shoulder, in effect, constitute suspenders. Attached to the waist band at suitably spaced 60 intervals is a series of buttons 8 for securing to this undergarment the outer trousers, such buttons being preferably secured to the band by loops 9 as illustrated.

The garment is cut down the front at 10 practically its entire length through such waist band and all, the edges being adapted to be secured together by means of a series of buttons 11 and button holes 12, one of the 15 buttons thus used, however, being one of the aforesaid buttons secured by means of a loop to the waist band, so that this particular button serves a double purpose.

At either side of the garment tabs 13 are secured to the band 7, such tabs being adapted 20 to have secured thereto garters or like fastening means (not shown) for the wearer's stockings.

In the rear, the garment is cut across on a transverse line 14 below the line of the waist-band 7 from one side to the other, and is also vertically opened at 15 on each side for some distance farther down, so that a flap is formed which may be opened downwardly, such flap being normally secured in closed 25 position by buttons 16 and button holes 17, as need not be further explained.

The foregoing garment presents a number of features of practical utility, as will be obvious from the description just given of 30 this construction and of the functions subserved by its several parts. In particular it will be observed that the bands 6 and 7 incorporated directly into the structure of the garment form a sort of harness from 35 which to suspend the appropriate garments with the burden resting as lightly as possible on the wearer, and over his shoulders at that, where such burden should properly be placed.

Other modes of applying the principle of my invention may be employed instead of the one explained, change being made as regards the mechanism herein disclosed, provided the means stated by any of the follow- 40

ing claims or the equivalent of such stated means be employed.

I therefore particularly point out and distinctly claim as my invention:—

- 5 1. In a garment of the character described, the combination of a drawer section and a waist section integral therewith, said garment having a vertical opening in front extending practically its entire length and a transverse opening in the rear just below the waist line, a vertical opening at each side communicating with such transverse opening so as to form a flap; adjustable shoulder straps for said waist; means for closing such front opening and flap, respectively; buttons spaced around the waist line for attaching an external garment; and a tab secured to such line at each side of the garment, adapted to have a garter, or the like, attached thereto.

2. In a garment of the character described, the combination of a drawer section and a waist section integral therewith, said garment having a vertical opening in front extending practically its entire length and a transverse opening in the rear just below the waist line, a vertical opening at each side communicating with such transverse opening so as to form a flap; adjustable shoulder straps for said waist; bands sewed to said waist and passing over such shoulder straps, respectively; another band similarly sewed around said waist and to the lower ends of said first-named bands; buttons and button-holes for closing such front opening and flap, respectively; buttons with loops securing the same at spaced intervals around said waist band, one such looped button serving also as a button to close such front opening; and a tab secured to such line at each side of the garment, adapted to have a garter, or the like, attached thereto.

3. In a garment of the character described, the combination of a drawer section and a

waist section integral therewith, said garment having a vertical opening in front extending practically its entire length and a transverse opening in the rear just below the waist line, a vertical opening at each side communicating with such transverse opening so as to form a flap; adjustable shoulder straps for said waist, a waist band sewed around the waist line, vertical bands sewed to said waist band and passing over said shoulder straps, buttons spaced around said waist band for attaching an external garment, said bands adapted to carry the weight of the garment and such external garment from the shoulders; and means for closing such front opening and flap respectively.

4. In a garment of the character described, the combination of a drawer section and a waist section integral therewith, said garment having a vertical opening in front extending practically its entire length and a transverse opening in the rear just below the waist line, a vertical opening at each side communicating with such transverse opening so as to form a flap; adjustable shoulder straps for said waist, a waist band sewed around the waist line, vertical bands sewed to said waist band and passing over said shoulder straps, buttons spaced around said waist band for attaching an external garment, a tab secured to such waist band at each side of said garment, adapted to have a garter or the like attached thereto, said bands being adapted to put the weight of the garment, the external garment and garter upon the shoulders of the wearer; and means for closing such front opening and flap, respectively.

Signed by me, this 2 day of July, 1915.
LOUIS H. HAYS.
